FILTER PANEL WITH ZIG-ZAG CORRUGATIONS

Jacob K. Brixius, Cleveland, Ohio, assignor to Air-Maze Corporation, Cleveland, Ohio, a corporation of Delaware

Application August 19, 1953, Serial No. 375,162

11 Claims. (Cl. 183—69)

This invention relates to improvements in a filter panel for filtering particles out of a gaseous stream.

One of the objects of the present invention is to provide a filter panel for removing entrained particles from a gaseous stream, wherein a plurality of generally parallel contiguous sheets of filter material are placed in a frame extending in the general direction of stream flow through the frame. Each of these sheets has parallel corrugations extending from the front face to the rear face of the panel, the corrugations of one sheet crossing the corrugations of the adjacent sheets in non-nesting relation. Each of these corrugations has a sharp bend intermediate the front and rear faces of the panel and the present invention relates to the positioning of these corrugation bends of one-half of the sheets in the panel at a fixed distance from one face of the panel while the corrugation bends of the alternate sheets of the panel are placed at a different fixed distance from the face of the panel.

Another object of the present invention is to provide a panel of the type described above whether or not the same is permanently mounted in a frame. In other words, the making of such a panel of disposable material such as paper, all of the sheets of which are firmly secured to each other and the finished panel being trimmed to a regular shape perimeter adapted to fit into a holding frame of corresponding perimeter. In such a case, the holding frame is a part of a permanent installation and the disposable panel can be removed from the permanent holding frame when the panel becomes dirty and replaced by a clean panel.

A further object of the present invention is the provision of a panel of the type described above and made of disposable material such as paper and mounted in a permanent substantially rigid frame individual to the panel but having a removable portion through which the disposable material of the panel may be extracted and a new panel substituted. In this case, the container frame for each individual panel is practically permanent while the filter material is disposable.

A further object of the present invention is the provision of a panel of the type above described formed of disposable material such as paper and having around it an individual panel frame of paper-like material laminated with a metallic foil on the outside faces of the frame. In this case, when the disposable panel is treated with a viscous adhesive, the adhesive will not come through the metallic foil covering the frame and protects the hands and clothes of the user against soiling. A still further object of the present invention is the provision of a filter panel of sheet material wherein the layers are secured together and terminate in a perimeter of predetermined shape, there being a slot provided intermediate the front and rear faces of the panel and extending continuously along at least two opposed sides of the panel, said slot extending from an edge of the panel inwardly, together with a strip of flexible sealing material held in the slot and extending outwardly beyond the edge

2

of the panel so that the strip of sealing material prevents the passage of the gaseous stream between the edge of the panel and a surrounding frame.

Other objects and advantages of my invention will be apparent from the accompanying drawings and description and the essential features thereof will be set forth in the appended claims. In the drawings Fig. 1 is a perspective view of a filter panel embodying my invention.

Fig. 2 is an enlarged fragmental sectional view taken along the line 2—2 of Fig. 1 and showing somewhat diagrammatically the arrangement of the corrugations in the various layers of a filter constructed according to my invention.

Fig. 3 is a fragmental sectional view similar to Fig. 2 and showing another modified form of my invention.

Fig. 4 is a transverse sectional view similar to Figs. 2 and 3 and showing still another modified form of my invention.

Fig. 5 is a perspective view of a fragment of a sheet of imperforate material corrugated for use in my invention.

Fig. 6 is a perspective view of a fragment of a sheet of foraminous material corrugated for use in my invention.

Fig. 7 is a fragmental sectional view similar to the right-hand end of Fig. 2 and illustrating the use of a novel sealing strip and also illustrating the construction of the frame using paper laminated with metal foil, while

Fig. 8 is a perspective view of a modified form of panel wherein a permanent substantially rigid frame is provided having a removal portion through which the panel may be extracted and a new panel substituted.

Filters have been made heretofore of a general character similar to those herein disclosed, but with a difference which will be hereinafter pointed out. My invention is applied to filter panels wherein a plurality of generally parallel sheets of filter material extend in the general direction of stream flow so that the flow of the gaseous stream through the filter panel is in general along the sheets of filter material rather than through them. One manner of constructing such a filter is shown in Fig. 1 wherein a generally imperforate frame 10 of rectangular form is made up of material which is channel form in section as clearly shown in Fig. 2. Sheets 11 of filter material are piled one on top of the other in the frame 10 until the frame is full, generally, the fourth side of the frame being left open for this purpose and then the last side is secured in position after the frame is filled.

My invention is applied by utilizing sheets of filter material such as shown in Figs. 5 and 6. Fig. 5 shows imperforate material which are sheets of heavy paper or metal or of metal foil. Fig. 6 shows foraminous material which might be the material of Fig. 5 perforated, but preferably is of screen mesh material corrugated as shown. It will be understood by those skilled in this art that it is difficult to clearly show the corrugated material in perspective as viewed in Figs. 5 and 6, but these figures will be understood by reference to Figs. 3 and 4 showing a Z form of corrugation which is that form which I have attempted to show in Figs. 4 and 5. In such a corrugation, a longer leg of the Z shape is indicated at 12 with shorter legs at 13 and 14. The bend between the legs 12 and 13 has been indicated at A and that between the legs 13 and 14 has been indicated at B. The same construction is illustrated in screen mesh material in Fig. 6 and therefore these same reference characters have been applied there with a prime suffix. Those skilled in this art will understand that such corrugations might have only a single bend as shown in Fig. 2.

In the prior art, as illustrated by U. S. Patent 2,567,030 granted September 4, 1951, to Oliver H. Schaaf, it was customary to place the bends in the corrugations of one layer substantially directly in registration with the bends of the adjacent layers. I have discovered that if these

bends are staggered as shown in Figs. 2, 3 and 4 improved efficiency results.

Referring now to Fig. 2, a corrugation of V form is shown having a longer leg 15 and a shorter leg 16 with the bend indicated at C. The view in Fig. 2 is broken away to show how the alternate layers are reversed in position so that in a first layer (toward the left in Fig. 2); the longer leg 15 is toward the front of the panel, then in the second layer next below it, the shorter leg 16 is toward the front of the panel and the longer leg toward the rear, then in the next layer beneath that the arrangement is as in the first one and the next layer beneath that is arranged as in the second one. This construction is followed through the panel. Thus, it will be seen that the bends C of one-half of the layers of filter material lie at a fixed distance D from the front face of the panel, while the bends of the other alternate layers of the panel lie along a second line which is at a different fixed distance E from the front of the panel.

Another form of my invention is shown in Fig. 3 wherein Z form corrugations somewhat like that shown in Figs. 5 and 6 are placed with the longer leg 12 toward the front of the panel at the left in Fig. 3 and the shorter legs 13 and 14 toward the rear of the panel. Then in the next layer beneath it, the shorter legs are at the front of the panel and the longer leg is toward the rear of the panel. The next layer beneath that is like the first described layer and the next layer beneath that, at the right in Fig. 3, is like the second described layer. In this form of my invention the longer leg 12 of the Z form corrugation is longer than the two legs 13 and 14 combined so that the position of the bends A and B of one layer is opposite the longer leg 12 of the layer on each side thereof. Here it is obvious that the bends A and B of one-half of the layers of filter material (the first and third described) lie along lines parallel to the front face of the panel but at a greater distance therefrom than the lines along which the bends A and B of the alternate layers lie (the second and fourth layers described).

In Fig. 4 I have shown another form of my invention wherein the first layer shown at the left in Fig. 4 is identical with the same layer of Fig. 3, the second layer moving toward the right and next below the first layer is like the first layer with the screen turned in reverse position, but with the longer leg 12 of the Z shaped corrugations cut off to give a shorter leg indicated at 12a. The next layer below this, the third one in Fig. 4 is like the first described and the next layer below that, the fourth one toward the right in Fig. 4 is like the second described layer. This again places the bends A and B of the first and third layers lying along lines parallel to the front face of the filter, but at a greater distance therefrom than the lines along which the bends A and B of the alternate layers 2 and 4 lie. The filter of Fig. 4 is similar to that described and claimed in my copending application Serial Number 375,122, filed August 19, 1953, for "Edge Filter Panel with Uneven Face."

The improved construction here shown in Figs. 2, 3 and 4 has a markedly higher efficiency than the older constructions shown in the above mentioned Schaaf patent. I believe this improved efficiency is due to the fact that turbulence occurs at the bends A and B of Figs. 3 and 4 or at the bends C of Fig. 2. By having these bends at different points with respect to the front of the panel in the alternate layers of the panel, I believe that I provide a greater turbulence of the gaseous stream passing through the panel and that the stream is thus more continuously stirred up in its passage through the panel than is true in the above-mentioned Schaaf panel. In any case, I find that my improved panel as shown in Fig. 3 will capture about 22% of the dirt which would pass through the construction shown in Fig. 2 of the above-mentioned Schaaf patent. This test was made with

foraminous screen mesh material of the same character in each case.

In Fig. 7 I have shown a form of seal which may be applied to the forms of the filter here shown or, indeed, to any filter composed of layers of filter material which are intended to be assembled in a surrounding frame.

Fig. 7 shows a portion of a filter constructed according to Fig. 2, the layers 11 and 11a being shown as alternately turned in opposite directions although other arrangements of filter material are contemplated. The filter is surrounded by a frame 17 which is shown in section in Fig. 7 as being generally of channel form and which it will be understood by those skilled in this art completely surrounds the filter panel around the perimeter thereof. Intermediate the front and rear faces of the panel a slot 18 is cut extending continuously along at least two opposed sides of the panel, and preferably, in many cases, around the entire perimeter of the panel. The reason I mentioned the limitation of "along at least two opposed sides of the panel" is because some sheets of panel material give a good seal along two opposed sides of a rectangular frame such as that shown in Figs. 1 and 8 but give a rather poor seal along the other two opposed sides of the rectangle. An uninterrupted strip 19 of flexible sealing material is inserted in the slot 18 and preferably is a snug fit in the slot so that it is held therein. The sealing strip extends outwardly beyond the outer edge of the filter panel so as to be in position to engage the web of the frame 17 in a manner to seal the opening there between the panel and frame against the leakage of any gaseous stream around the right-hand edge of the filter panel as seen in Fig. 7.

One form of sealing strip is made of usual felt material used for sealing purposes. Another and preferred form of sealing strip is made of laminated tissue or wadding paper. Such a laminated paper structure is sold under the trade name of Kimpak.

Fig. 7 illustrates another improvement which may be utilized in connection with my invention. Where the panel is made of disposable material such as paper, and where the frame is also made of paper as illustrated in Fig. 1, the filter panel is often coated with a viscous adhesive so as to cause the dirt particles to adhere more easily and more efficiently to the filter material. In such a case, the viscous adhesive works through the paper frame 10 of Fig. 1 and soils the clothes and hands of the user. In Fig. 7 I have illustrated a frame 17 which is made of paper laminated with a metal foil 17a on the outside surfaces thereof. It results from this construction that while the main paper portion 17 of the frame may become coated with viscous adhesive and impregnated with viscous adhesive and impregnated therewith clear through the paper, nevertheless, the metal foil 17a is impervious to the viscous adhesive, which quite often is oil, and therefore the outer surfaces of the frame remain clean for handling.

Another manner of utilizing my invention is illustrated in Fig. 8. Here the frame 20 may be of channel form metal or other rigid material as previously described with the corners 21 and 22 permanently fixed in position, but with the corner 23 left non-rigid so that it may provide a hinging action as illustrated in the movement of the top panel 20a from the full line position to the dot-dash position of Fig. 8. When the filter is first made the top panel 20a is moved downwardly after all of the filter elements are in place and the bolt or other means 24 holds the free end of the side 20a to the adjacent side so as to maintain the frame in its rectangular condition. When the filter is to be serviced the bolt or other securing means 24 is removed, the panel 20a is moved to its dot-dash position or higher, sufficiently to permit the removal of the filter element 25 from the frame. This filter element may preferably be made of paper or other disposable material so that it is thrown away when dirty and a new clean element placed in the frame 20. The fourth side

20a is then closed down again to the full line position and fastened with the bolt or securing means 24. In this fashion, I make it possible to utilize the frame 20 over and over again while the filter element 25 may be thrown away and replaced each time it becomes dirty.

Still another manner of utilizing my invention, is to secure all of the sheets of the filter element together and trim it or build it so that it has a perimeter of predetermined contour so as to fit into a permanent holding frame. Those familiar with this industry will understand that a frame like 10 or 20 is normally slipped into a holding frame and held there by means of clips or other removal securing means. Instead of providing the individual frames 10 or 20 for each filter panel, I may trim the filter element itself to the shape of the holding frame so that it may be pushed into position and held there by any suitable means and then thrown away when the filter becomes dirty. In a preferred form of my invention, where the filter is made up of paper or the like as previously described, these layers may be permanently secured to each other by a strong adhesive so that the entire filter panel becomes a single block which may be trimmed to the desired shape and handled in a manner above indicated.

What I claim is:

1. In a filter panel for removing entrained particles from a gaseous stream and having front and rear faces and frame means compelling stream flow through said panel from the front face to the rear face, a plurality of generally parallel contiguous sheets of filter material extending in the general direction of stream flow, each of said sheets having parallel corrugations extending from the front face to the rear face of said panel, the corrugations of one sheet crossing the corrugations of adjacent sheets in non-nesting relation, each of said corrugations having a bend between the front and rear faces of said panel and the corrugation bends of one sheet being at a substantially different distance from a given face of the panel with respect to any corrugation bends of the adjacent sheets on each side of it.

2. The combination of claim 1 wherein said sheets are of substantially imperforate material.

3. The combination of claim 1 wherein said sheets are of foraminous material.

4. The combination of claim 1 wherein said sheets are of foraminous screen mesh material.

5. The combination of claim 1 wherein said corrugations are generally Z form with one leg of said Z being longer in a fore-and-aft direction than the other two legs combined, whereby said two shorter legs of one sheet will lie opposite the long leg of sheets on opposite sides thereof, all of said sheets being uniformly corrugated and alternate sheets being turned upside down when assembled in said panel.

6. In a filter panel for removing entrained particles from a gaseous stream, a plurality of generally parallel contiguous sheets of disposable material such as paper extending in the general direction of stream flow, each of said sheets having parallel corrugations extending from the front face to the rear face of said panel, means main-

taining said sheets in non-nesting relation, a frame of paper-like material completely surrounding the perimeter of said panel, said frame being laminated with a metallic foil layer on the outside faces thereof, whereby when said panel is treated with a viscous adhesive, said foil protects the user from contact with said adhesive.

7. A filter panel for removing entrained particles from a gaseous stream comprising a filter element, a frame completely surrounding the perimeter of said filter element and substantially in engagement therewith, there being a slot intermediate the faces of said panel extending into said panel from an edge thereof and a strip of flexible sealing material held in said slot and extending outwardly therefrom beyond the edge of said panel, said strip engaging the interior face of said frame whereby to seal against leakage along the edge of said panel where it is adjacent said frame.

8. The combination of claim 7 wherein said flexible sealing strip extends substantially continuously, completely around the perimeter of said panel.

9. The combination of claim 7 wherein said sealing strip comprises a plurality of laminated layers of tissue paper.

10. The combination of claim 7 wherein said sealing strip is of felt.

11. In a filter panel for removing entrained particles from a gaseous stream and having front and rear faces and frame means compelling stream flow through said panel from the front face to the rear face, a plurality of generally parallel contiguous sheets of filter material extending in the general direction of stream flow, each of said sheets having parallel corrugations extending from the front face to the rear face of said panel, said corrugations being generally inclined relative to the face of said panel, the corrugations of one sheet crossing the corrugations of adjacent sheets in non-nesting relation, each of said corrugations having a sharp bend between the front and rear faces of said panel, the corrugations of every other sheet having their bends lying along a line substantially parallel to the front face of the panel at a fixed distance therefrom, and the corrugations of the others of said sheets having their bends lying along a line substantially parallel to the front face of the panel and at a different fixed distance therefrom, whereby the corrugation bends of one sheet are at a substantially different distance from a given face of the panel with respect to any corrugation bends of the adjacent sheet on each side of it.
